UNITED STATES PATENT OFFICE.

CHARLES DIMECH, OF JACKSONVILLE, FLORIDA.

CARTRIDGE-PRESS.

1,318,649.

Specification of Letters Patent. Patented Oct. 14, 1919.

Application filed September 12, 1918. Serial No. 253,691.

To all whom it may concern:

Be it known that I, CHARLES DIMECH, a citizen of the United States, residing at Jacksonville, in the county of Duval, State 5 of Florida, have invented a new and useful Cartridge-Press; and I do hereby declare the following to be a full, clear, and exact description of the invention, such as will enable others skilled in the art to which it 10 appertains to make and use the same.

The present invention relates to a die stamping press for the manufacture of small arms cartridges, and has for its object to provide a device of this character which 15 embodies novel features of construction whereby the several steps of die stamping are simultaneously performed at each operation or revolution of the main drive shaft, thereby completing a cartridge at each revolution and enabling large quantities of 20 cartridges to be turned out with despatch by unskilled labor.

Further objects of the invention are to provide a cartridge press of this character 25 which is simple in its construction, which provides for automatically feeding the cartridges through the machine as the stamping progresses, which is automatic in its action after the material is fed thereto, which has 30 no complicated or delicate parts to get out of repair or adjustment, and which provides for adjusting the automatic feed of the die blocks so that the movement thereof will be in exact synchronism with the up and 35 down movements of the punches.

With these and other objects in view, the invention consists in certain novel combinations and arrangements of the parts as will more fully appear as the description 40 proceeds, the novel features thereof being pointed out in the appended claims.

For a full understanding of the invention, reference is to be had to the following description and accompanying drawings, in which:—

Figure 1 is a side elevation of a cartridge press constructed in accordance with the invention.

Fig. 2 is an end view thereof.

Fig. 3 is a side elevation with parts broken away and shown in section to illustrate more clearly the details of construction.

Fig. 4 is a transverse sectional view on the 55 line 4—4 of Fig. 3.

Fig. 5 is an enlarged sectional view

through portions of the cross head and one of the die blocks, showing the plungers in operative position within the die openings.

Fig. 6 is a top plan view of one of the die 60 block members.

Fig. 7 is an enlarged detail sectional view of the adjustable connection between the cam rod and the wrist pin of the crank disk.

Fig. 8 is an enlarged detail view of a portion of the gearing which is utilized for feeding the die blocks.

Fig. 9 is a detail view showing a slight 70 modification.

Corresponding and like parts are referred to in the following description and indicated in all the views of the drawings by the same reference characters.

Referring to the drawings, which illustrate one embodiment of the invention, the numeral 1 designates a table which may be suitably mounted upon standards 2, the upper face of the table being formed with a grooved guideway 3 over which a series 75 of detachably connected guide blocks 4 travel with an intermittent motion when the machine is in operation. A frame 5 projects upwardly from the table 1 and has a heavy cross head 6 slidably mounted thereon for vertical reciprocating movement. A pair of pitmen 7 connect the top of the cross head 6 to crank portions 8 of a main drive shaft 9 which is horizontally disposed and is journaled in suitable bearings 80 85 provided on the frame 5. Fly wheels 11 are applied to opposite ends of the main shaft 9 and power may be applied to this shaft in any suitable manner. It will be obvious that as the shaft is rotated the cross head 90 95 6 will be moved up and down, and one end of the shaft is provided with an eccentric 12 which operates the means for feeding the die blocks.

A series of punches 13 project downwardly from the cross head 6, said punches successively increasing in length in the direction in which the die blocks travel, and being properly shaped to perform the successive stamping operations which are required to complete the cartridge. Ordinarily seven stamping operations are required for this purpose, and in the present instance the cross head 6 is provided with seven of the punches 13 which project downwardly therefrom and gradually increase in length from one end of the cross head to 100 105 110

the opposite end thereof. Each of the die blocks 4 is also provided with seven die openings 14, said die openings being spaced in a manner corresponding to the spacing 5 of the punches 13, and the feeding mechanism being arranged to impart a step by step movement to the die blocks so that in the operation of the machine each of the die openings 14 is brought successively 10 under the several punches 13. Since all seven of the stamping operations are accomplished at each revolution of the main shaft, it will be understood that one complete cartridge will be turned out at each 15 operation of the machine, thereby enabling large quantities of the cartridges to be manufactured and turned out complete in a short period of time. The die blocks 4 travel in the grooved guideway 3, being provided 20 with side flanges 15 of which one is toothed to form a rack, and which travel under flanged guide strips 16 secured to the top of the table. The guide blocks are thus free to travel longitudinally across the table, 25 although they are held securely against lateral displacement, and the flanged guide strips 16 prevent them from being lifted up with the punches.

The toothed side flanges or racks 15 of the 30 die blocks are engaged by a pinion 17 at the upper end of a vertical shaft 18, the lower end of the vertical shaft being connected by bevel gearing 19 to a horizontal shaft 20 which has a ratchet gear 21 fitted 35 thereon. This ratchet gear is of the conventional construction, being locked with the shaft to rotate the same when turned in one direction, and turning independently of the shaft in the other direction. An oscillating gear wheel 22 meshes with the ratchet gear 21, and is connected by a pitman 23 to a crank disk 24. A slide 25 extends diametrically across the face of the crank disk 24 and carries a wrist pin 26 which is engaged 40 by the lower end of a cam rod 27, the upper end of the cam rod being provided with a strap 28 which extends around the before mentioned eccentric 12 of the main drive shaft 9. The ends of the slide 25 terminate in threaded stems upon which nuts 29 are threaded, thereby providing for locking the slide and wrist pin 26 in an adjusted 45 position. As the main shaft 9 revolves the eccentric 12 reciprocates the cam rod 27 and 50 this oscillates the crank disk 24, the amplitude of the oscillation depending upon the adjustment of the wrist pin 26, becoming greater as the wrist pin is moved away from the center of the disk. This movement of 55 the crank disk 24 is transmitted to the oscillating gear 22 through the pitman 23, with the result that the ratchet gear 21 is rotated back and forth to produce an intermittent or step by step movement of the die blocks 60 across the top of the table 1. By adjusting 65

the position of the wrist pin 26 the movement of the die blocks can be brought into exact synchronism with the movements of the punches, and the adjustment is such that the die blocks remain stationary while the punches are lowered into the die openings 14, although they are advanced a distance equivalent to the spacing between the punches each time the punches are raised. The several die openings are thus brought 70 successively under the different punches 13, with the result that the metal therein is properly stamped and shaped, the last punch being constructed to project the completed cartridge shell from the machine, 75 and one complete cartridge shell being produced at each reciprocation of the cross head.

The die blocks 4 are arranged end to end and have a detachable pivotal connection so that they are fed through the machine in the form of a continuous chain, thereby avoiding all unnecessary handling of the material. One end of each of the die blocks is formed with a tongue 30, while the opposite end 80 thereof is correspondingly recessed at 31, the tongue of each block being received within the recess of the adjacent die block and connected thereto by a pivot pin 32 which passes loosely through corresponding 85 openings therein. The connection between the die blocks is such that a proper spacing of the die openings 14 in the chain of die blocks is maintained throughout the length thereof, and the die blocks can be 90 readily detached from each other at one end of the chain and connected at the opposite end of the chain. The operation of stamping the cartridge blanks is thus enabled to be performed rapidly, since the seven necessary stamping operations are performed at 95 one time instead of successively, and the output of an operator is thus greatly multiplied.

A slight modification is shown by Fig. 9, in which an idler 37 is interposed between 100 the pinion 17 and the rack 15 of the die block. This extra pinion provides for increasing or decreasing the speed with which the die blocks move, as may be necessary 105 when the cartridge press is operating under 110 different conditions.

Having thus described the invention, what I claim as new and desire to secure by Letters Patent, is:—

1. A press of the character described, including a table, a vertically movable cross head mounted above the table, a series of punches projecting downwardly from the cross head and increasing successively in length and decreasing successively in diameter from one end of the series to the opposite end thereof, die blocks slidable across the top of the table under the cross head and provided with a series of die openings 120 which are identical in shape and each of 125 130

which has distinct portions adapted to co-operate with the corresponding punches, and means for reciprocating the cross head and moving the die blocks in synchronism therewith to bring the die openings successively under the punches.

2. A cartridge press including a table provided with a guideway in the top thereof, a frame above the table, a cross head vertically movable upon the frame, a series of punches projecting downwardly from the cross head, a chain of detachably connected die blocks slidably mounted within the guideway of the table and provided with a series of die openings corresponding to the punches, a drive shaft journaled upon the frame and operatively connected to the cross head, a cam on the drive shaft, a crank disk, a wrist pin projecting from the crank disk, a cam rod connecting the cam and wrist pin, an oscillating gear member driven from the crank disk, and means actuated by the oscillating gear member for producing a step by step movement of the die blocks in synchronism with the cross head and bringing the die openings thereof successively under the punches.

3. A cartridge press including a table having a guideway in the top thereof, a frame above the table, a cross head vertically movable upon the frame, a series of punches projecting downwardly from the cross head, a chain of detachably connected die blocks slidably mounted within the guideway of the table top and provided with a series of die openings corresponding to the punches, a drive shaft journaled in the frame and operatively connected to the cross head, a cam on the drive shaft, a crank disk, a wrist pin projecting from the crank disk, a cam rod connecting the cam and wrist pin, an oscillating gear wheel driven from the crank disk, a ratchet gear wheel meshing with the oscillating gear wheel, and means actuated by the ratchet gear wheel for producing a step by step movement of the die blocks in synchronism with the cross head to bring the die openings successively under the punches.

4. A cartridge press including a table having a guideway extending across the top thereof, a frame above the table, a cross head vertically movable upon the frame, a

series of punches projecting downwardly from the cross head, a chain of detachably connected die blocks slidable within the guideway of the table and provided with side flanges of which one is toothed to form a rack, guide members overhanging the flanges to hold the die blocks against upward displacement, a pinion meshing with the rack of the die blocks, a drive shaft journaled upon the frame and operatively connected to the cross head, and means actuated by the shaft for intermittently moving the pinion and advancing the die blocks step by step in synchronism with the cross head to bring the die openings successively under the punches.

5. A cartridge press including a table having a guideway extending across the top thereof, a frame above the table, a cross head vertically movable upon the frame, a series of punches projecting downwardly from the cross head, a chain of detachably connected similar and interchangeable die blocks slidable within the guideway of the table and provided at their sides with flanges of which one is toothed to form a rack, guide members overhanging the said side flanges to hold the die blocks against upward displacement, a pinion meshing with the rack of the die blocks, said die blocks being provided with die openings corresponding to the punches, a drive shaft journaled upon the frame and operatively connected to the cross head, a cam on the drive shaft, a crank disk, a wrist pin projecting from the crank disk, a cam rod connecting the cam and wrist pin, an oscillating gear wheel operatively connected with the crank disk, and a ratchet gear wheel meshing with the oscillating gear wheel and operatively connected with the pinion to produce an intermittent step by step movement of the die blocks in synchronism with the cross head and bring the die openings thereof successively under the punches.

In testimony whereof I have signed my name to this specification in the presence of two subscribing witnesses.

CHARLES DIMECH.
